UNITED STATES PATENT OFFICE.

WALTER H. COTTON, OF CHICAGO, ILLINOIS, ASSIGNOR TO THE ADAMS & WESTLAKE COMPANY, A CORPORATION OF ILLINOIS.

POLE-CHANGER.

No. 868,968.

Specification of Letters Patent.

Patented Oct. 22, 1907.

Application filed August 6, 1906. Serial No. 329,407.

To all whom it may concern:

Be it known that I, WALTER H. COTTON, a citizen of the United States, and a resident of Chicago, county of Cook, and State of Illinois, have invented certain new and useful Improvements in Pole-Changers, of which the following is a specification, and which are illustrated in the accompanying drawings, forming a part thereof.

The invention relates to that class of pole changers which are serviceable in connection with reversible dynamos; its object being to provide a simple and effective device of this character.

The invention consists in the mechanism herein-after described, and which is illustrated in the accompanying drawings, in which—

Figure 1 is a face view of the pole changer, an electric generator and circuit being diagrammatically shown; Fig. 2 is a sectional view of the pole changer on the line 2—2 of Fig. 1; Fig. 3 is a detail sectional view 20 of the pole changer on the line 3—3 of Fig. 2; Fig. 4 is a diagrammatic view of the device showing a different circuit arrangement.

A dynamo is conventionally represented at 10 and its field at 11 and as being in series with the lamp circuit 12.

The pole changer comprises a base-plate 13, having apertured lugs 14 and 15 to provide for securing it to a proper support. The plate 13 is shown as circular in form, and secured at its margin, and suitably insulated, 30 are a pair of oppositely-disposed segmental contact-plates 16, 17, and intermediate thereof, and equi-distant therefrom, two pairs of oppositely-disposed contact-plates 18, 19 and 20, 21, the members of each pair being insulated each from the other but each being connected to a member of the opposite pair, a strap 22 uniting the plates 18 and 20, and a strap 23 uniting the plates 19 and 21.

The plate 13 is provided with a centrally apertured hub 24, within which is fixed a shaft 25. Upon the outer end of this shaft is rotatably mounted a disk 26, carrying a pair of segmental plates 27, 28, each having at its ends a pair of radially-projecting contact-pieces 29, 30 and 31, 32. The contact-pieces 29, 32, are constantly in engagement with the plates 16 and 17, the latter being of a width equal to the range of movement of the shiftable parts. Each of the other contact-pieces 30 and 31 alternately engage one of each pair of the intermediate plates 18, 19 and 20, 21. The plate 26 carries a pin 33, which projects through an elongated aperture 34 in the plate 13 and is engaged by an oscillating yoke 35, pivoted on a stud 36, projecting from the rear face of the plate 13. The yoke 35 is provided with a finger 37, which rides upon the periphery of a disk 38, mounted with a worm-wheel 39 on the shaft 25. The worm-wheel 39 is driven by a worm 40 on a

power-driven shaft 41, which is actuated from the armature shaft of the dynamo 10, and hence is turned in either direction. The disk 38 has a pocket 42 setting in from its periphery, into which the finger 37 falls at each rotation of the disk, the width of the yoke 35 engaging the pin 33 being sufficient to allow the finger to drop into this recess.

With the parts in the position shown in Fig. 3, so long as the disk 38 continues to turn to the left, that is, reverse of a clockwise movement, the switch remains 65 undisturbed in the position shown in Fig. 1, the finger 37 dropping into the recess 42 and immediately rising therefrom as the disk proceeds. Upon a reversal of direction of the disk 38, the finger 37 enters the recess 42 and is carried to the right, past the perpendicular, when it again rides up onto the periphery of the disk. Upon thus being moved to the right, the yoke carries the pin 33 with it and shifts the plate 26, bringing the 70 plate 28 into contact with the plate 18 and the plate 27 with the plate 21. The next reversal of direction of rotation of the shaft 38 will restore the switch to the position shown.

As represented in Fig. 1, the circuit is traced from 75 the positive brush of the dynamo 10 to the contact-plate 18, through the strap 22 to the contact-plate 20, through the plate 27 to the contact-plate 16, through the line 43 to the field circuit 11, thence through the line 44 to the plate 17 and through the plates 28 and 19 80 to the light circuit 12, and thence to the negative brush of the dynamo. Upon the reversal of the dynamo the polarity of the brushes is changed and the switch or pole changer is shifted. The positive lead is now directly from the dynamo to the lamp circuit 12 85 through the line 45, thence through the plate 19, the strap 23, the plates 21, 27 and 16, the line 43, the field 11, the line 44, the plates 17, 28 and 18, and the line 46 to the dynamo.

In Fig. 4 the same form of pole changer is diagrammatically represented, there being shown a storage battery, the light battery and field circuits being served from the same dynamo and being arranged in parallel. The circuit is led from the dynamo through the lines 47, 48, to the pole changer, and from the latter to the 90 lines 49, 50. Branches 51, 52, connect with the storage battery 53, branches 54, 55, lead to the lamp circuit 56, and branches 57, 58, connect with the field 11.

I claim as my invention—

1. In a pole changer, in combination, an oscillatable switch, a reversible rotatable wheel having a recess in its periphery, and an oscillatable member having a lost motion connection with the switch and having a point bearing on the wheel and adapted to enter the recess.

2. In a pole changer, in combination, an oscillatable switch, a reversible rotatable wheel having a recess in its periphery, an oscillatable yoke engaging a stud on the switch and having the arms of the yoke spaced apart more

than the diameter of the stud, and a finger projecting from the yoke and riding on the wheel.

3. In a pole changer, in combination, a fixed plate, two pairs of diametrically-disposed contact plates mounted in such plate, two diametrical contact plates intermediate of such pairs of plates each of a width equal to the combined width of the two members of each pair of plates, electric conductors permanently connecting opposed members of the two pairs of plates, an oscillatable plate, a

pair of contact plates carried thereby and each adapted to engage one of the wider contact plates with either member of one of the pairs of plates, and means for oscillating such carrying plate.

WALTER H. COTTON.
